METHOD FOR REFINING USED CRANKCASE OIL

William D. Harris, Kansas City, Mo.

Application May 15, 1942, Serial No. 443,030

2 Claims. (Cl. 196—16)

This invention relates to a method for rendering available for further use in engines, crank case oil which has become contaminated to an extent which ordinarily would render it a waste product. It has been demonstrated by the present inventor that the valuable lubricating properties of oil are not destroyed after ordinary use in an engine, and in fact it has been proved repeatedly that such used oil displays a greater stability than it possessed when it was newly produced from the refinery. This is explained by the action of the engine in supplementing the original refining process by breaking down the unstable constituents remaining in newly refined oil through the combined effects of heat and mechanical agitation. It will follow therefore, that if the contaminating constituents of the used oil are removed, the reclaimed oil will be superior in at least some respects to freshly refined oil.

Methods for refining used oil have been proposed previously in the United States Letters Patent of Aycock and Harris, No. 1,707,671, granted on April 2, 1929, and Patrick, No. 1,750,350, granted on March 11, 1930; and apparatus for carrying out such methods has been described in United States Letters Patent of Harris and Aycock, No. 1,707,672, granted on April 2, 1929, and Krieger No. 1,820,871, granted on August 25, 1931. The method of the present invention represents vast improvement over the prior art teachings in reducing the time and expense of operating and in facilitating the cleansing of the apparatus employing my method.

In the methods employed in the prior art, oil in the still is heated to a relatively high temperature, and when the distillation is complete, this heat is entirely wasted. In accordance with this invention, when the oil is drawn from the still, it is brought into heat exchange relationship with a new batch of oil to be refined, thereby preheating the new batch with a consequent saving of time and expense.

The elements of an apparatus to carry out the steps of my method are interconnected by suitable piping and valves so as to facilitate travel of the oil through the system with a minimum of equipment and handling, and to permit cleansing of the parts by the circulation of fluid from one receptacle to another, merely by the operation of a few valves.

The manner of achieving the foregoing objects will be more clearly understood by referring to the accompanying drawing which is hereunto annexed and is a part of this specification.

The single figure is a somewhat schematic ele-

vation partly broken away, showing an apparatus capable of performing the present invention, although it is recognized that various forms of apparatus may be employed, therefore I only show one which has been demonstrated in practice to be efficient for the purpose intended.

The still 10, supported in a suitable frame 12, comprises an outer shell 14 and an inner shell 16 suitably spaced from the outer one for insulating purposes. The inner shell is constructed to withstand relatively high internal and external pressures. The still is provided with an inlet opening 18, and an outlet opening 20 surmounted by a dome having an inner wall 22 and an outer wall 24 spaced therefrom by a flange 26. The dome is covered by a cap 28, having suitable threads 30 for connection with a fitting 32 to which a safety valve 34 and a distillate tube 36 are connected. Through suitable fittings, the opposite end of the distillate pipe is connected to the upper end of a condenser coil 38, supported in a condenser tank 40. The lower end of the coil 38 is connected through a pipe 42 and gage glass 44, with a condensate or dilution tank 46.

Cooling water for the condenser is supplied from a suitable source through a valve 48 and pipe 50 to the inlet opening 52 at the lower end of the condenser tank 40, whereupon it passes in countercurrent heat exchange relationship with the coil 38 and emerges through an outlet port 54 to a water pump 56 through a pipe 58. The pump 56 discharges through an outlet 60 to a conveniently located sewer connection. The suction side of the pump 56 is connected through a pipe 62, stop valve 64 and check valve 66 to the upper portion of the dilution tank 46 so that by proper manipulation of the valves, the dilution tank and still can be subjected to a partial vacuum.

The dilution tank is supported upon a bracket 68 projecting from the frame 12, and may be anchored by means of suitable straps 70. The still is fastened to the frame 30 in a similar manner by straps 72. The dome of the still is fitted with a plurality of alternate disks 74 and rings 76 arranged to form a cartridge and depending from the cap 28. One or more electric heating elements 78 are fitted through the still wall to serve as the source of heat. Each element is enclosed within a casing 80 which is successively coated with nickel and chromium and highly polished to resist corrosion and facilitate cleaning. The still is also provided with a clean-out opening 82 which is normally closed by a cover 84. Other fittings include a thermometer 86 to indicate still temperatures, a drain cock or air

vent 88 in the pipe line 42 between the condenser coil and the dilution tank, a drain cock 90 for the dilution tank itself, a pressure gage 92 in the water supply line, and a vacuum gage 94 connected in the suction line, shown as attached to the dilution tank.

The frame 12 is provided with a platform 96 for supporting an open top contact vessel 98 directly below the still. This contact vessel is preferably of an inner wall 100 and an outer wall 102 spaced therefrom and filled with suitable heat insulating material 104. The bottom of the contact vessel is provided with an outlet opening 106, which through suitable piping 108 and a stop valve 110, is connected with the intake side of a pump 112. Another opening 114 is provided near the bottom of the contact vessel, which connects it by a length of pipe 116 with the lower end of a heat exchange coil 118 supported within a heat exchange and mixing tank 120. The upper end of the heat exchange coil 118 is connected through a nipple 122, valve 124, four-way fitting 126 and valve 128 with an opening 130 formed nearer the top of the contact vessel 98. The lower branch of the four-way fitting 126 is connected through a suitable pipe line 132, a T-fitting 134, and a four-way fitting 136, with the delivery side of the pump 112. The pipe line 132 is provided with an intermediate branch pipe 138 which, through a stop valve 140, feeds a retort washer nozzle 142 passing through the cover 84. The upper branch of the four-way fitting 126 is connected with a pipe 144, containing a stop valve 146, terminating in a branched line. One branch is connected through a stop valve 148 with a pipe 150 leading to an opening 152 at the bottom of the mixing tank 120; the other branch includes a pipe 154, which is in turn branched to connect with the still inlet opening 18 through a pipe 156 on the one hand, and through a stop valve 158 to a contact vessel feed pipe 160, on the other. An agitator 162 is suitably clamped on the wall of the mixing tank 120, with its shaft 164 carrying blades at its lower end.

A by-pass 164 is connected in the line 108 intermediate the contact vessel and the valve 110, which, through a stop valve 166, communicates with the T 134. The pump delivery line is provided with a pressure gage 168, which may be connected at the four-way fitting 136. The upper branch of the four-way fitting 136 is connected through a stop valve 170 with the inlet of a filter press 172. The outlet of the press is connected through a stop valve 174 with a filler pipe 176, and through a stop valve 178 and pipe line 180 with a nozzle 182 located above the contact vessel 98.

The used oil to be refined by the present process should be treated first with sulfuric acid in an open vessel. Particularly heavy oil may require thinning with kerosene if the best results are to be achieved. After the used oil has settled, it is agitated during the addition of 66 degree Baumé sulfuric acid (commercial 1.1835 specific gravity) in approximate proportions of up to one gallon of acid to fifty gallons of oil. The addition of acid and agitation should be continued however until the carbon particles become separated as distinct specks about the size of a pin head or larger and the oil between the particles is in a clear condition. The thus treated oil is then permitted to stand for a period ranging from six to eighteen hours, during which the acid

sludge will settle and the oil will be clear of the carbon particles.

Assuming that all valves and cocks of the apparatus have been closed, the valve 48 will be opened and circulation begun through the condenser tank 40 and the pipe 58 to the pump 56 and discharge through the outlet 60 to the sewer. The valve 64 is also opened so as to establish communication between the pump and the dilution tank 46, condenser coil 38 and still 10, thereby reducing the still pressure to a sub-atmospheric value.

The oil to be treated is transferred to the mixing tank 120 preferably, so as to cover the heat exchange coil 118 and the agitator 162 set in operation. To fifty gallons of such oil there is added 20 to 22 pounds of a sulfuric acid treated clay such as "Retrol," a well known product of the Filtral Corporation. This clay serves to restore the original color to the oil, particularly at elevated temperatures. After these materials have been thoroughly mixed, the bottom of the mixing tank 120 is placed in communication with the still 10 by opening the valve 148, whereupon the vacuum created by the pump 56 will elevate the mixture into the still. The valve will then be closed and current will be supplied to the heating element or elements 78. The mixing tank 120 will then be supplied with a new batch of oil to be treated in accordance with steps to be described subsequently.

As the temperature in the still rises, some water will probably be distilled off, and by maintaining a relatively slight vacuum, all of the moisture 35 can be removed without experiencing excessive foaming. When the still temperature reaches about 325° F., the degree of vacuum should be increased gradually by properly manipulating the valves, and if it appears from the gage glass 44 that part of the oil itself is passing to the dilution tank, the cock 88 can be opened to vent the system to an extent necessary to correct this condition. By careful observation of the gage glass, it is possible to obtain a maximum degree 45 of vacuum in the system by the time and still temperature reaches about 425° F., depending upon the desired viscosity of the end product. After the necessary heat has been supplied, the circuit to the heater is opened, yet the flow of condensing water may be continued for a brief period. However, when all of the distillate to be removed has been condensed, the valve 48 will be closed, which will of course, stop the action 50 of the pump 56. At this point, the valves 124 and 146 between the still inlet and the contact vessel port 114 may be opened for a moment for the purpose of sucking air into the still and thereby clearing this pipe line of any obstructions. The vacuum in the system is then broken 55 by opening the vent 88 and at this time, the dilution tank 46 may be drained by opening the cock 90.

The product remaining in the still requires some further treatment with reagents, which is carried out in the contact vessel 98. Into this vessel there is deposited for each fifty gallons of oil being treated, about 8 pounds of a clay of the type of 200 mesh fuller's earth, one such product being known commercially as "Refinolite Compound #1," and about 1/2 pound of an oil insoluble neutralizing agent such as the material sold on the open market as "F. C. D. X."

Then the valves 146 and 124 are opened to permit oil to flow from the still into the heat exchange coil 118, wherein heat is transferred from

the hot oil to the new batch in the mixing tank. The agitator 162 will be set in operation at this time so as to mix the new batch of oil with 20 to 22 pounds of the "Retro" clay already referred to, which is described in trade-mark registration No. 304,074 as a chemically treated colloidal clay adapted for use as a decolorizing, bleaching, filtering, purifying and absorbing medium.

The hot oil flowing through the coil 118 will pass through the pipe 116 into the contact vessel 98 where it encounters the treating agents previously placed therein. When all of the oil has flowed from the still, which can be determined by the height of oil in the contact vessel 98 or by opening the valve 128, the valves 146 and 124 will be closed and the valve 128 opened. The valve 110 in the suction line 108 is also opened and operation of the pump 112 is started. Oil is then drawn from the bottom of the vessel 98 through pipe 108, valve 110, pump 112, and returned to the contact vessel through pipe 132 and valve 128. When this circulation has been established, valve 140 leading to the still is opened and valve 128 is closed. Then valve 158 is opened so that the hot oil flushing through the still will remove any loose composition which may have settled therein and cause it to flow into the contact vessel. The valve 124 leading to the heat exchange coil 118 is next opened and the valve 140 closed. The circulation is now from the bottom of the contact vessel, through the pump and coil, and back into the contact vessel. When the still has ceased draining through the pipe 160, the valve 158 will be closed.

The water pump 56 is again started by opening the valve 48, and when a sufficient vacuum has been established, the valve 148 is opened to draw the new batch of oil from the mixing tank into the still. The agitator 162 will be stopped when the oil level in the tank drops. When all of the oil has been drawn from the tank 120 into the still, the valve 148 is closed and the distillation process will proceed as before. The valve 124 is then closed and the valve 128 opened so that circulation from the contact vessel to the pump and back to the contact vessel will be re-established, and during all of this time, the distilled oil is being cooled in preparation for its passage through the filter press 172.

The valve 170 leading to the filter press and the valve 178 leading therefrom are next opened so that oil from the bottom of the contact vessel passes through the pump, part of it passing through the filter press, valve 178, pipe 180 and nozzle 182 to the contact vessel, the remainder through the pipe 132 and valve 128 to the contact vessel. Thus it will be seen, that by adjusting the valve 128, the pressure of the oil applied to the filter press can be regulated rather readily. When the filtered oil discharged from the

nozzle 182 is sufficiently clear, the valve 178 will be closed and the valve 174 opened, so that the completely refined oil will be delivered through the pipe 176 to suitable containers. In the event of leakage in the press, the pipe line 183 from the bottom of the press to the intake side of the pump is provided, which may be connected through a stop valve for breaking and establishing flow.

10 The foregoing process represents a preferred form to utilize the present invention, but it is to be understood that the various elements described are not to be construed as limitations except where they are set forth in the appended claims.

15 Having described my invention what I regard as new and desire to secure by Letters Patent is:

1. Process of re-refining of used oil comprising the following steps: creating a vacuum in a still, causing a body of oil to be treated which is under atmospheric pressure to be drawn through a conduit into said still by the vacuum, vaporizing the diluents from the oil in said still, after said diluents have been vaporized, causing the vacuum to draw air through said conduit to cleanse the same, breaking the vacuum in said still, drawing off the re-refined oil from said still to a contact vessel, cooling said re-refined oil on its way to said contact vessel by passing it in heat-exchange relation with a batch of oil to be re-refined, then circulating said oil repeatedly in a cyclic path from said contact vessel in heat-exchange relation to said batch of oil and back to said contact vessel, by-passing a portion of said oil from said cyclic path and discharging it into the bottom of said still under pump pressure to remove any deposit in said still, discharging said deposit and the by-passed portion of the oil from the still and returning it to the cyclic path.

2. Process of re-refining of used oil comprising the following steps: creating a vacuum in a still, causing a body of oil to be treated which is under atmospheric pressure to be drawn through a conduit into said still by the vacuum, vaporizing the diluents from the oil in said still, breaking the vacuum in said still, drawing off the re-refined oil from said still to a contact vessel, cooling said re-refined oil on its way to said contact vessel by passing it in heat-exchange relation with a batch of oil to be re-refined, then circulating said oil repeatedly in a cyclic path from said contact vessel in heat-exchange relation to said batch of oil and back to said contact vessel, by-passing a portion of said oil from said cyclic path and discharging it into the bottom of said still under pump pressure to remove any deposit in said still, discharging said deposit and the by-passed portion of the oil from the still and returning it to the cyclic path.

WILLIAM D. HARRIS.
